UNITED STATES PATENT OFFICE.

JOHN CRAWFORD MOORE, OF LOWER EDMONTON, LONDON, ENGLAND.

DOOR-CLOSER OR DOOR-CHECK.

1,130,923.

Specification of Letters Patent.

Patented Mar. 9, 1915.

Application filed April 28, 1913. Serial No. 764,280.

To all whom it may concern:

Be it known that I, JOHN CRAWFORD MOORE, a subject of the King of Great Britain, residing at Nightingale Hall, 5 Lower Edmonton, London, England, have invented new and useful Improvements in Door-Closers or Door-Checks, of which the following is a specification.

This invention relates to improvements in or relating to door closers or door checks the object thereof being to effect improvements in or relating to single or double acting door closers or door closers and door checks which will operate equally well on right and 15 left hand doors without any change in the mechanism whatsoever without a ratchet.

The improved device is easy to assemble and easy to take part, simple of construction, most efficient in action and one which it is 20 impossible for the liquid to leak from as the case is not perforated in any part where the liquid is contained.

In order that this invention may be fully understood it will now be described with 25 reference to the accompanying drawings in which:—

Figure 1 is a plan of the device. Fig. 2 is a front elevation with the arms removed. Fig. 3 is a side view of the casing. Fig. 4 30 is a plan with the cover and horizontal bevel wheels removed for the purpose of more clearly showing some of the parts. Fig. 5 is an irregular longitudinal vertical section partly in elevation and viewed from the 35 back of the casing. Fig. 6 is a detailed section on line X, X, of Fig. 5. Fig. 7 is a detailed view of the spring tensioning adjuster. Fig. 8 is a side elevation of the tube valve. Fig. 9 is a view at right angles to 40 Fig. 8. Fig. 10 is a partially sectional side elevation of the same.

As shown in the drawings, the device comprises the casing *a*, cylinder *b* and cover or lid *c*, all secured on the top of the door. 45 Arranged within the casing *a* is a removable block *d* supporting a vertical bevel wheel *e* directly connected by a rod *f* with the piston head *g* while in the block *d* the lower extremity of the rotary spindle *h* is journaled. 50 The upper extremity of this spindle passes through and is supported by the lid *c* while it carries near its lower extremity a horizontal bevel wheel *e'* meshing with the afore-mentioned bevel wheel *e*. 55 Upon vertical posts *i* the springs *j* which are made right and left handed are arranged

and supported around collars *k*, the latter being maintained apart by sleeves *k'*. The upper extremities *k*² of these springs are secured to a tensioning yoke *l* through the 60 medium of links *l'* and adjusted by the screw *l*² (Fig. 2 and Fig. 7) while their lower extremities *k*³ are connected by chains *m* with the perforated and elongated lugs *n* (Fig. 6) carried by the vertical spindle *h* 65 (Fig. 6) the holes in the said lugs being elongated or of elliptical form as shown.

Referring now more particularly to Figs. 1 to 3 of the drawings, on the upper outside extremity *h'* of the spindle *h* is pivoted on 70 the transverse pin *o* by means of a screw as shown in Fig. 1 the split portion *o'* of the spindle arm the said arm being completed by the rod *p* screwing therein, the bracket arm comprises the curved rod *q* pivoted to 75 the arm *p* and the rod *q'* linked to *r* as at *r'*. The rods *q* *q'* are provided with a right and left handed screw thread respectively and connected together by the link *q*² as shown for the purpose of adjustment. 80 Upon the lid *c*, the eccentrically placed cam *s* is formed while the split portion *o'* of the spindle arm is constructed with a heel or extension *o*² both of the latter bearing thereon when the door is closed to keep it steady 85 in this position.

The bracket *r* is provided with a spring *t* (Figs. 1 and 2) for giving the door an initial start when the door is fully opened away from the side the casing is on and the 90 springs *j* lose their power by reason of the joint connecting the arms being more or less in line with the dead center *r'*, this start being effected by the said spring coming into contact with the rod *q'* of the bracket arm. 95

The valve and by-pass mechanism intended for use in connection with this combined door closer and check and which is more clearly shown in Figs. 5, 8, 9 and 10 of the drawings comprises a tube *v* having 100 a screw threaded enlarged solid shoulder *v'* designed to screw into the cover or lid *c* and a milled head *v*² for convenience in manipulating the same. This tube *v* which passes closely through a hole *g'* in the piston *g* has a lower bore *w* of a larger diameter than the upper bore *w'* the two being connected by a portion forming a seating for the ball *w*² the latter being prevented from leaving the tube by the cross pin *w*³. The 105 tube *v* is furnished with fluid inlets *y* at a point above the travel of the piston, and 110

near the bottom with fluid passages y' or the open end while it is likewise formed with a flat or reduced circumference z which serves as a by-pass.

5 In operation, when the piston is raised by the swinging open of the door, the fluid is sucked through the openings y and passes the ball w^2 and out through the exits y' or the open end to supply fluid to the under-surface of the piston while upon the door being released and the piston g forced down under the action of the springs j which have previously been tensioned, the ball w^2 assumes the position shown in dotted lines 10 (Fig. 10) and closes the tube v , when the fluid can only return to the space above the piston through the bypass formed by the flat z , or reduced circumference the extent of the latter being varied according to 15 requirements. It will be seen that the action of this valve is extremely simple and effective while it can be readily removed for inspection or repair or for permitting fluid to be readily supplied to the cylinder and 20 casing.

In practice, the casing of the device is intended to be secured to the door and the bracket r to the lintel while it is equally suitable for single acting right or left handed doors or for double acting doors. Upon the rotary spindle h being turned in either direction by the opening swing of a door, it will be seen that the springs j are tensioned through the medium of the connecting chains m rolling the required distance 30 around said spindle connected by the lugs n , while the piston is raised by the bevel wheels e, e' and connecting rod f . Upon the door being released, the latter is closed 35 by the reaction of the springs, through the reverse turning of the rotary spindle h , the closing force being transmitted through the spindle and bracket arms, $o' p$ and q, q', q^2 while the slow descent of the piston, by reason 40 of the closing of a valve, in the tube passing therethrough and the provision of a by-pass in connection with the same serves to control the speed of the door.

I am aware that a yoking plate connecting the extremities of two longitudinally stretched spiral springs with an adjusting screw passing through the spring casing and the plate for adjusting the tension of the

springs has been employed in connection with door closers and also in connection with door checks a tube passing through the check piston has been provided for permitting the flow of the fluid from one side to the other of the said piston and I make no claim broadly for these features.

Having now particularly described and ascertained the nature of my said invention and in what manner the same is to be performed, I declare that what I claim is:

1. In a door closer, the combination with 65 a vertical rotary spindle carrying a cross-piece outside the casing a forked lever arm pivotally connected to said crosspiece and eccentrically disposed cam ring surrounding the upper extremity of said rotary spindle, 70 which ring has an upward graduating surface adapted to bear against said forked lever arm, and designed to move it in a vertical manner, substantially as and for the purpose specified.

2. In a door closer the combination with 75 a vertical rotary spindle carried in a casing on the top of the door, which spindle is operated by the opening of the door against the force of springs of a bracket secured on 80 the lintel of the door which bracket carries a spring, of a lever arm connected to said bracket bent laterally at its outward extremity from said bracket, which bent part is designed to pass underneath the lintel of 85 the door, and the straight part thereof operates against the spring on said bracket when the door is opened to about 95 degrees 90 of a circle away from the side said casing is on.

3. In a door closer with a casing secured on a door carrying a vertical rotary spindle which is adapted to be turned by the opening of the door, of springs located around 95 separately supporting spindles on said casing flexible bands which connect said rotary spindle with these springs in such a manner that whichever way this rotary spindle is turned these springs are tensioned.

Signed at Edmonton, Middlesex, Eng- 100 land, this 4th day of April 1913.

JOHN CRAWFORD MOORE.
